Primary Examiner — Elizabeth A. Albert(74) *Attorney, Agent, or Firm* — Michael Best & Friedrich LLP(57) **CLAIM**

We claim the ornamental design for a cap for writing utensil, as shown and described.

DESCRIPTION

FIG. 1 is a perspective view of a cap for writing utensil showing our new design.

FIG. 2 is a front view of FIG. 1.

FIG. 3 is a rear view of FIG. 1.

FIG. 4 is a first side view of FIG. 1.

FIG. 5 is a second side view of FIG. 1.

FIG. 6 is a top view of FIG. 1; and,

FIG. 7 is a bottom view of FIG. 1.

The broken lines are included to show portions of the cap for writing utensil that form no part of the claimed design.

1 Claim, 4 Drawing Sheets**US D924,969 S**
